UNITED STATES PATENT OFFICE

JOHN L. FINNEGAN, OF NASHVILLE, TENNESSEE

FLUSH VALVE

Application filed October 1, 1928. Serial No. 309,500.

This invention relates to flush valves for water closet and other service systems, and particularly to flush valves of that type for automatically performing a flushing action at predetermined time periods.

One object of the invention is to provide a flush valve which is simple of construction, reliable and efficient in action, and which may be varied in action for automatic service to vary the flushing periods as desired.

Another object of the invention is to provide a flush valve which may be operated by hand, if desired, without disrupting its normal automatic action, or which may be adjusted for hand operation when an automatic action is not desired.

Still another object of the invention is to provide a flush valve which will automatically refill a waste trap by drainage action.

With these and other objects in view, the invention consists of the features of construction, combination and arrangement of parts, hereinafter fully described and claimed, reference being had to the accompanying drawings, in which:

Figure 1 is a vertical longitudinal section through a flush valve embodying my invention, showing the parts in cut off position or as they appear between flushing periods.

Figure 2 is a section through one side of the valve taken at right angles to that shown in Figure 1.

Figure 3 is a horizontal section on line 3-3 of Figure 1.

Figure 4 is a vertical section taken through the valve casing at a point where one of the casing fastenings is applied.

Figure 5 is a horizontal section on line 5-5 of Figure 1.

Figure 6 is a horizontal section on line 6-6 of Figure 1.

Figure 7 is a horizontal section on line 7-7 of Figure 1.

Figure 8 is a horizontal section on line 8-8 of Figure 1.

Figure 9 is a horizontal section on line 9-9 of Figure 1.

In the practical embodiment of my invention I provide a flush valve comprising a valve casing 1 preferably formed in three

horizontally divided sections 2, 3 and 4, to wit, a central or body section 2, a bottom section 3, and a top section 4, said sections being detachably united at suitable intervals around the valve casing by fastening screws 55 or bolts 5, as shown in Figure 4.

The casing section 2 is divided by a horizontal partition 6 into a pressure compartment 7 and a release compartment 8, the said pressure compartment being separated from the bottom section 3 by a diaphragm 9 of rubber or other elastic material, while the compartment 8 is separated from the top section 4 by a similar diaphragm 10. The section 3 provides a discharge or flush compartment 11 while the section 4 provides a flush controlling or regulating compartment 12.

The compartment 11 is provided with a water supply inlet 13 for connection with a waste service pipe and with a discharge outlet 14 for connection with the toilet or other fixture or apparatus to be flushed. Disposed within the compartment 11 and separating the same except at its top from the outlet 14 is a valve seat tube 15 within which is mounted a discharge or flush valve 16 having a guide tube 17 formed with discharge ports 17' therein. This valve comprises upper and lower members 18 and 18^a in threaded engagement with each other and clamped to the diaphragm 9, the member 18 forming a weight for normally opposing a determined resistance to the upward movement of the diaphragm and opening movement of the valve under pressure in the compartment 11 and opposing pressures in the compartments 7 and 11. As shown, the valve member 18^a is of less diameter than the valve member 18 and tube 15, so that the diaphragm is made to serve as a portion of the valve to seat against the upper edge of said tube. When the valve is in the position shown in Figure 1 the flow of water from the pipe 13 to the outlet 14 is cut off, the valve being held in closed position against the normal service pressure of the water by a preponderating pressure in the compartment 7.

When the pressure in the compartment 7 is relieved so that it becomes less than the pressure in the compartment 11, the valve 16 10³

opens upwardly for the flow of water from the service pipe 13 over the upper edge of tube 15 and through the passage 17' and tube 17 into the lower portion of tube 15 and thence to the outlet 14.

Formed in one side of the valve casing is a water flow passage 18' extending between the compartments 7 and 11 and controlled by a needle valve 19. A valve casing 20 together with a pipe 21 and a passage 22 in casing section 4 connects the compartment 7 with the compartment 12, and a needle valve 23 in said valve casing 20 governs the flow of water from the compartment 7 into this connection, while a similar valve 23' in the passage 22 of said connection governs the flow of water from said connection into the compartment 12. All three valves 19, 23 and 23' are removable for cleaning, repairs or other purposes and are adjustable from the exterior for regulating the time flow of the water between the compartments or for cutting off the flow of water when desired. The valve 23' is preferably set so that the compartment 12 will be filled for a flush regulating action within a given period of time after having been emptied, while the valve 19 is so adjusted as to effect a replenishment of the pressure compartment 7, after each flush action, within less periods of time than required to replenish the compartment 12 so that after each flush action the valve 16 will be automatically closed for a cut off action by the pressure in the compartment 7 while the compartment 12 is being refilled for the subsequent flushing action. While valve 19 is maintained in action, valve 23 may be closed when desired to cut out the automatic action and permit the valve device to be manually operated, as hereinafter described, without disturbing the adjustment of valve 23', which may be left set as long as it is desired to maintain flush actions at predetermined periods in the automatic operation of the valve.

The casing is formed to provide an annular well 24 coextensive in depth with the chambers 7 and 8 and communicating with the chamber 8 at its top and communicating at its bottom with a drain passage 25 leading to the discharge outlet 14. This well is filled with water flowing from chamber 7 to chamber 8, as hereinafter described, and the water is retained in said chamber 8 and well 24 until the end of a flushing action through the main valve 16 on account of a preponderance of pressure in the outlet 14 at all times except at the end of a flushing action. A passage 26 and pipe 27 connect the outlet 14 with the top of chamber 8 to allow air to enter during the discharge of water from said chambers 12 and 8 and the well 24.

The partition 6 is provided with a port affording communication between the compartments 7 and 8, said port having a valve

seat 28 against which a relief valve 29 is adapted to close upward. The relief valve is carried by a hollow or cylindrical stem 30 depending from the diaphragm 10 and carried by a clamping member 31 engaging the underside of the diaphragm. This clamping member 31 is in threaded engagement with a clamping member 32 bearing against the diaphragm 10 within the chamber 12, said clamping member having a passage communicating with the stem 30 and provided with a seat 33 for a vertically movable ball float valve 34, said valve being movable upwardly and downwardly in a cage formed by rods 35 extending between the member 32 and a head plate 36, carrying a tubular guide tube or nipple 37 through which the float valve stem extends, said stem comprising telescopic sections 38 and 39, the former fixed to the ball and the latter slidably in the nipple 37, the section 38 having at its upper end a contact head 38' and the section 39 having at its upper and lower ends contact heads 39^a and 39^b. A coiled spring 40 is disposed in the compartment 8 about the stem 30 and about a stationary guide tube 41 carried by the partition 6 and in which said stem is movable, said spring operating to close valve 29 against its seat 28 to allow compartment 7 to fill through 19 and 18^b to cut off flushing action. Ports 42 are formed in the stem 30 for communication with the chamber 8 and well 24 when the valve 39 is opened for the flow of water from the relief compartment 7 through ports 43 in the guide tube 41 into the chamber 8 and thence into the well 24 and drain passage 25.

The guide tube or nipple is movable in a guide opening in a wall 44 having also a guide opening for the stem 39 and a stop or abutment 45 on which the head 39^a of the stem is adapted to rest to limit the downward movement of the valve member 34. Projecting from the top of the casing is a bonnet 46, closed by a cap 47 and having arranged therein a bushing 48 and a washer 49, said washer being clamped with a rubber or other elastic disk 50 against a shoulder on the exterior of the bonnet. Movably mounted in the bonnet and attached to the disk 50 is a plunger stem 51 normally held raised by a spring 52 and carrying a button, knob or like actuating device 53 projecting outwardly through the cap 47, by means of which the plunger may be manually depressed against the resistance of the spring. On the underside of the disk 50 is a contact piece 54 adapted, on the depression of the plunger, to engage the guide tube or nipple 37 whereby motion may be transmitted through the float valve cage to the diaphragm 10 to force said diaphragm downwardly for a manual opening of the relief valve 29 for a hand-operated flush action. A clamping screw 55' is provided on cap 47.

which may be tightened against plunger stem 51 to hold the plunger from movement, when it is desired to set the device for automatic operation only.

5 The operation is as follows:

Figure 1 shows the device in normal or cut-out position, the valves 16 and 29 being closed and the valve 34 and diaphragms appearing in the positions they occupy at the 10 end of an after-fill operation and water is flowing through valves 23 and 23' to compartment 12. Compartment 12 is refilled within a determined period according to 15 setting of valve 23' to regulate the automatic flushing intervals. When compartment 12 is filled to produce the required pressure on diaphragm 10, the latter descends against the resistance of spring 40 and pressure in compartment 7 and opens 20 valve 29, whereupon, owing to the reduced pressure in compartment 8 and well 24 as compared with that in compartment 7, a primary relief action takes place through a flow of a portion of the water from compartment 7 through ports 42 and 43 into compartment 8 and well 24. Valve 16 now opens and water flows to outlet 14 from compartment 11 and inlet 13 for a main flushing action. During these actions float valve 34 remains 30 closed, but the diaphragm 10 continues to descend until contacts 38^a and 39^b engage, thus holding valve 34 from further downward movement while the diaphragm 10 continues to move downward to its limit. 35 On such further downward movement of diaphragm 10 valve 34 is lifted off its seat 33, and since the valve 34 is buoyant its stem section 38 slides upward on its stem section 39, and water flows from the compartment 12 into compartment 8 and well 24. The pressure in compartment 12 being thus relieved 40 spring 40 closes valve 29 allowing pressure to be built up in compartment 7. The pressure in the compartment 7 now causes valve 45 16 to close to cut off the main flush, and immediately thereafter compartment 12 empties into compartment 8 and well 24, 25 and outlet 14, and float valve 34 returns by gravity to the 50 position shown in Figure 1. During the main flush, the pressure in the outlet 14 being greater than that in chamber 8 and well 24, the water contained in said chamber and well is retained therein. As soon, however, as the main flush ceases and valves 16 and 29 55 are closed, the water in compartments 8, 12 and well 24 drains into outlet 14 for an after-flush or after-fill action. Water now feeds through valves 19, 23 and 23' to the compartments for a replenishing action and for a repetition of the flush action as soon as the pressure in compartments is raised again to the 60 predetermined degree.

Should it be desired to operate the flush manually, this may be effected at any time 65 between automatic flushes, with the compartment

ment 12 filled to any degree, by depressing the plunger 51, if screw 53' is released, without interfering with any adjustment of the parts used in the automatic action. The device may be converted into a manually operable, or hand flush device, by simply maintaining screw 53' in retracted position and closing the valve 23 to cut off the flow of water to the chamber 12, so that upon manually opening the valve 29 for a relief of pressure in compartment 7 the valve 16 may be opened for a flush action. This may be done while the apparatus is left in condition for a restoration of an automatic flush action, whenever an automatic action is desired, by 80 simply opening the valve 23 again.

From the foregoing description, the construction and operation of my improved flush valve will be readily understood, and it will be seen that a valve having the capabilities and advantages stated is provided which is of simple construction and may be manufactured and sold at a comparatively low cost. This valve may be readily and conveniently 85 installed, not liable to get out of working order, and in the event of derangement of any of its parts, may be easily and conveniently repaired. While the construction shown is preferred, it will, of course, be understood that changes in the form, proportions, and details of construction may be made within the scope of the appended 90 claims without departing from the spirit or sacrificing any of the advantages of the invention.

Having thus described my invention, I claim:

1. A flush valve comprising a casing having a water inlet and a water outlet, a pressure controlled discharge valve governing the outlet, a pair of pressure compartments and a relief compartment in the casing, said relief compartment having a drain outlet, a pair of valve members controlling communication at timed intervals between the pressure compartments and the relief compartment, one of said valve members having a flow passage and the other of said valve members controlling said passage, and valve devices governing a flow of water from the inlet to the pressure compartment.

2. A flush valve comprising a casing having a water inlet and a water outlet, a pressure controlled valve governing the flow of water from said inlet to said outlet, a pressure compartment to the pressure conditions of which said valve is subjected, a relief compartment communicating with the outlet, a regulating compartment, valved regulating passages controlling the flow of water to the pressure and regulating compartments, an automatically closing relief valve movable under pressure in the regulating compartment to establish communication between the relief and pressure compartments, and

- a valve adapted to open under a predetermined opening movement of the relief valve to open communication through said relief valve between the regulating and relief compartments. 5
3. A flush valve comprising a casing having a water inlet and a water outlet, a pressure controlled valve governing the flow of water from said inlet to said outlet, a pressure compartment to the pressure conditions of which said valve is subjected, a relief compartment communicating with the outlet, a regulating compartment, valved regulating passage controlling the flow of water to the pressure and regulating compartments, an automatically closing relief valve movable under pressure in the regulating compartment to establish communication between the relief and pressure compartments, and a float 10 valve in the regulating compartment adapted to open upon a predetermined movement of the relief valve to open communication through said relief valve between the regulating and relief compartments. 15
4. A flush valve comprising a casing having a water inlet and a water outlet, a pressure controlled valve governing the flow of water from said inlet to said outlet, a pressure compartment to the pressure conditions of which said valve is subjected, a relief compartment communicating with the outlet, a regulating compartment, valved regulating passages controlling the flow of water to the pressure and regulating compartments, an 20 automatically closing relief valve movable under pressure in the regulating compartment to establish communication between the relief and pressure compartments, a valve in the regulating compartment adapted to be 25 opened by the relief valve after a predetermined movement of said relief valve to establish communication between the regulating and relief compartments, and manually adjustable means for controlling and regulating the movements of said valves for making the same operative automatically or manually at will. 30
5. A flush valve comprising a casing having a water inlet and a water outlet, a pressure controlled valve governing the flow of water from said inlet to said outlet, a pressure compartment to the pressure conditions of which said valve is subjected, a relief compartment communicating with the outlet, a regulating compartment, valved regulating passages controlling the flow of water to the pressure and regulating compartments, a hollow automatically closing relief valve movable under pressure in the regulating 35 compartment to establish communication between the pressure and relief compartments, said valve having a portion for opening and closing communication between said compartments and having a passage for connecting the relief and regulating compartments, 40
- and a float valve in the regulating compartments controlling said passage in the relief valve and adapted to open under a predetermined movement of said relief valve to establish communication through the passage between the regulating and relief compartments. 45
- It testimony whereof I affix my signature.
